UNITED STATES PATENT OFFICE.

ANNIE R. KEENAN, OF PITTSBURGH, PENNSYLVANIA.

DETACHABLE TRIMMING FOR LOW SHOES.

Application filed June 12, 1922. Serial No. 567,771.

To all whom it may concern:

Be it known that I, ANNIE R. KEENAN, a citizen of the United States, and resident of Pittsburgh, in the county of Allegheny and State of Pennsylvania, have invented a new and useful Improvement in Detachable Trimmings for Low Shoes; and I do hereby declare the following to be a full, clear, and exact description thereof.

10 My invention relates to a detachable trimming for low shoes or oxfords.

It has lately become the style, more especially in connection with women's shoes, to provide low shoes with different colored trimmings, these trimmings being sewed or otherwise permanently secured to the shoe, and where it is desired to have these trimmings match the gown it is necessary to have a separate pair of shoes for each gown. The 20 object of my invention is to provide a detachable trimming for low-shoes which may be quickly and readily applied to the shoes or removed therefrom, so that it is possible to have a number of different sets of trimmings of various colors to be applied to the same pair of shoes. In this way a person of moderate means is able to have the equivalent of several pairs of shoes with trimmings of different colors for the price of one pair 30 of shoes, and the slight additional costs of the separate trimmings.

To these ends my invention consists, generally stated, in a detachable trimming for low-shoes consisting of a saddle-like attachment fitting over the instep and terminating short of the heel with an elastic portion engaging the shank of the shoe, and provided with eyelets for the laces for securing the trimming in place, the eyelets registering with the eyelets of the shoe, so that the same lace may be passed through both sets of eyelets, or at least some of the eyelets of the shoe.

45 In the accompanying drawing, Fig. 1 is a perspective view of a shoe showing my detachable trimming fitting thereon; Fig. 2 is a like view broken away, showing how the lace passes through the uppermost eyelets of both the shoe and the trimming; and Fig. 50 3 is a perspective view of my improved trimming.

In the drawing, the numeral 2 designates a low-shoe or oxford which may be made of canvas, leather or any other suitable ma-

terial, and provided with the ordinary eyelets 3 for the lace 4.

The detachable trimming 5 may be formed of leather or any other suitable material, and of any desired shade or color, said trimming having the elastic 6 which is adapted to engage the shank of the shoe, and said trimming having the slit 7 extending part way down the front so that the trimming has to be slipped over the toe of the shoe and brought up into position over the instep 65 with the elastic 6 engaging the shank.

The trimming is also provided with the eyelets 8 to receive the lace 4, and said eyelets preferably register with the eyelets of the shoe so that the same lace may be 70 passed through the eyelets of the shoe, or at least a portion of said eyelets, so that when the trimming is drawn up by the laces to form a close fit the shoe will at the same time be fitted to conform to the instep, terminating short of the heel.

The trimming when applied in this manner, as shown in Fig. 1, will have all the appearance of being attached to and forming part of the shoe, especially as the stitched edges 9 will give it the appearance of being sewed to the shoe. The trimming when once applied to the shoe and the laces drawn up and tied, fits neatly and is held securely against shifting or displacement, so that it 85 will always present a neat attractive appearance.

These trimmings may be made up in many different shades, and it is possible for the owner of one pair of shoes to possess a number of sets of trimmings of various colors so as to have trimmings which will match the different gowns and the change from one set of trimmings to another may be made quickly.

What I claim is:

A detachable trimming for low-shoes comprising a saddle-like member fitting over and conforming to the instep of the shoe and terminating short of the heel, having an elastic portion engaging the shank of the shoe, a slit formed part way down the front, and lacing eyelets adapted to register with the eyelets of the shoe.

In testimony whereof, I, the said ANNIE R. KEENAN, have hereunto set my hand.

ANNIE R. KEENAN.
